UNITED STATES PATENT OFFICE.

ALBRO J. MORSE, OF BALTIMORE, MARYLAND.

APPARATUS FOR TREATING GARBAGE.

No. 910,407.

Specification of Letters Patent.

Patented Jan. 19, 1909.

Application filed April 26, 1905. Serial No. 257,517.

To all whom it may concern:

Be it known that I, ALBRO J. MORSE, a citizen of the United States of America, and resident of Baltimore city, State of Maryland, have invented certain new and useful Improvements in Apparatus for Treating Garbage, of which the following is a specification.

My invention relates to certain new and useful improvements in a method and apparatus for treating garbage and the like.

The object of my invention is to reduce garbage or like material which requires digesting or rendering. By my method and apparatus, the digesting can be completed more quickly, more efficiently and with a greater saving in cost of fuel than has heretofore been possible.

With these objects in view, my invention consists in the method of treating garbage or the like which consists in placing the same in a jacketed digester passing superheated steam at high temperature and low pressure through the jacket of the digester and agitating the material in the digester.

My invention also consists in a rotary digester provided with a jacket and means for introducing superheated steam at high temperature and low pressure into a jacket while the digester is being rotated.

My invention also consists in certain details of construction and combination of parts, the preferred form of construction of which will be first described and then the invention particularly pointed out in the claims.

Referring to the drawings wherein I show the preferred form of my apparatus, Figure 1 is a diagrammatic view showing as much of a plant as is necessary to understand the invention. Fig. 2 is a detail sectional view of one end of the digester showing the connections therewith. Fig. 3 is a similar view showing the other end of the digester.

1 designates the boiler of any desired construction and 2 a superheater, 3 is a steam pipe leading from the boiler to the superheating coil 4 in the superheater.

5 is a pipe leading from the superheating coil to the digester 6. The digester is composed of an outer shell 7 provided with the heads 8 and 9 and an inner shell 10 which is provided with the heads 11 and 12. The inner shell is supported by suitable means within the outer shell so as to stand in the center thereof.

13 are man-holes which extend into the inner shell in order to give access to the inner shell for the filling of the inner shell with the material which is to be digested and the removal of the material therefrom.

14 is a stuffing box provided in the head 9 of the outer shell and in this stuffing box is mounted a pipe 15 which at its inner end is provided with a ring 16. To the free end of this pipe is connected a coupling 17 which connects the end of the steam pipe 5 with the pipe 15, whereby superheated steam can pass from the superheater through the pipes 5 and 15 into the outer shell of the digester.

18 is a pipe which extends through the opening in one side of the coupling 17 and is bent at right angles passing through the central portion of the pipe 15 and into the outer shell between the head 9 and the head 12. This pipe then turns down so that its open end extends down to nearly the lower portion of the outer shell. The other end of this pipe is connected to a steam trap 19. By this construction, it will be seen that the water of condensation which forms in the outer shell will be drawn off by this pipe and the trap in the usual manner. It will also be observed that by the stuffing box construction shown and described, the pipes 15, 18 and 5 remain stationary and the digester may revolve, the stuffing box allowing this without the escape of steam.

At the other end of the digester from that which is provided with the construction shown in Fig. 1, is a construction shown in Fig. 3, in which 20 is a pipe passing through a stuffing box 21 in the outer shell and into the inner shell. At the inner end, the pipe is provided with a T-head 22 which has extending upwardly from one end thereof the open pipe 23 and at the other end of the T-head, I preferably provide a perforated disk 24. Connected to the outer end of the pipe 20 is a pipe 25 which leads to a suitable condenser, not shown. By this construction, all vapors which form in the inner shell are drawn off from the digester and condensed. By this construction, the material to be digested may be digested under as little pressure as desired. By having the pipe 23 extending to the upper portion of the shell as shown, the liability of material dropping into the pipe is minimized and should any material so pass in, it will immediately pass through the perforated disk 24.

Preferably, I connect the pipe 25 to the

5 pipe 20 by, a T-head 26. Through this T-head, I pass a suitable thermostat 27, the thermostat closing the open end of the T-head and passing into the pipe 20 nearly to 10 the T-head 22. This thermostat is connected by a pipe 28 to the valve 29 located in the main steam pipe 5, whereby the amount of steam supplied to the outer shell will be controlled by the temperature in the inner shell 15 and by properly adjusting the thermostat, any desired temperature may be maintained within the inner shell.

30 designates supports for the digester and these supports may be driven in order to rotate the digester or any other suitable means 15 may be provided therefor.

In the operation in carrying out my invention, when the forms of apparatus is used here shown and described, the material to 20 be digested is placed in the inner shell through the man-holes 13 which are then closed. A low pressure is preferably maintained in the boiler at not over 10 to 15 pounds. The steam from the boiler then 25 passes through the superheater where it may be superheated to any desired temperature up to eight to nine hundred degrees if such a temperature should be found desirable. By maintaining a low pressure in the boiler 1 30 and because of the circulation of steam through the superheater, this high temperature of the superheater steam is obtained without materially increasing the pressure of the steam. The steam then passes through 35 the superheater and through the pipes 5 and 15 into the other shell of the digester. A suitable safety valve may be provided in the digester in order to prevent the pressure therein from rising to more than 10 or 15 40 pounds. The digester being rotated keeps the material therein in constant agitation and evenly and quickly digests the whole mass. The steam which condenses passes out 45 through the pipe 18 and may be trapped at 19 and maintain the desired pressure in the jacket. The vapors which are given off by 50 the material being digested are carried away by the pipe 25 to a suitable condenser. As these vapors, when they enter in the section 55 20 to which the pipe 25 is connected, are practically of the temperature of the material in the digester, the thermostatic valve will operate to keep the material in the digester at any desired temperature which should not be sufficiently high to carbonize 60 the grease or volatilize the nitrogen contained in the material.

By the use of low pressure superheated steam in the manner described, the use of 65 stay-bolts to connect the inner and outer

shells of the digester is entirely done away with, which largely reduces the cost of the digester. In addition to this, because of the low pressure the apparatus can be used for a 65 much longer time, since the acids contained in the material being digested eats away the iron or steel from which the digesters are made and since they are subject to a low pressure will last much longer than the ordinary form of digester in which high pressure is used.

It will be evident that the apparatus described in this application is equally well 75 adapted as a drier and that material to be dried may be placed in the inner shell and rapidly and efficiently dried if desired, the temperature of the superheated steam being regulated to produce the desired result and the condenser operating to carry the moisture and vapors as given off by the material being dried. It is to be further noted that by the use of this digester, no water is added to the material to be digested during the operation, and consequently, the operation can 85 be carried on more rapidly than when the steam is passed directly through the material to be digested which adds a large percentage of water to the material.

While I have described the preferred form 90 of my invention, I desire to have it understood than many changes may be made there-in without departing from the spirit thereof.

Having fully described my invention what I claim as new and desire to secure by Letters Patent is:—

1. In an apparatus for treating material, the combination with a jacketed tank, of means for superheating steam at low pressure and introducing the same in the jacket 100 of the tank, means for rotating the tank to agitate the material therein and means for withdrawing from the tank the moisture given off by the material.

2. In an apparatus for treating material, 105 the combination with a jacketed tank, of means for superheating steam at low pressure and introducing the same in the jacket of the tank, means for rotating the tank to agitate the material therein means for withdrawing the water of condensation from the jacket means for regulating the supply of superheated steam to the jacket and withdrawing from the digester the moisture given off by the material.

Signed by me at Washington, District of Columbia, this 25th day of April 1905.

ALBRO J. MORSE.
